UNITED STATES PATENT OFFICE.

FRANK P. KEMPF, OF CHICAGO, ILLINOIS.

DESIGN FOR AN ANIMAL DOLL.

Application filed October 5, 1927. Serial No. 23,639. Term of patent 3½ years.

To all whom it may concern:

Be it known that I, FRANK P. KEMPF, a citizen of the United States, residing at Chicago, in the county of Cook and State of Illinois, have invented a new, original, and ornamental Design for an Animal Doll, of which the following is a specification, reference being had to the accompanying drawings, forming part thereof.

Fig. 1 is a side elevational view of my animal doll; and

Fig. 2 is a plan view of the same.

I claim:

The ornamental design for an animal doll, as shown.

FRANK P. KEMPF.
